(57) **CLAIM**

The ornamental design for a notebook computer, as shown and described.

DESCRIPTION

FIG. 1 is a perspective view of the notebook computer, having an approximately rectangular sub-display (screen) being positioned at a top of a keyboard;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view.

The broken lines shown in the drawings illustrate portions of the notebook computer that form no part of the claimed design.

1 Claim, 7 Drawing Sheets
